UNITED STATES PATENT OFFICE.

HARVEY W. RICHARDS, OF PORTLAND, OREGON, ASSIGNOR TO SCORE MINING COMPANY, OF PORTLAND, OREGON.

AMALGAMATOR SUPPORT.

Application filed May 2, 1922. Serial No. 557,916.

To all whom it may concern:

Be it known that I, HARVEY W. RICHARDS, a citizen of the United States, residing at Portland, in the county of Multnomah, State of Oregon, have invented certain new and useful Improvements in Amalgamator Supports; and I do hereby declare the following to be a full, clear, and exact description of the invention, such as will enable others skilled in the art to which it appertains to make and use the same.

This invention relates to new and useful improvements in amalgamators, and particularly to skids or supports therefor.

One object of the invention is to provide skids of the character named which are adjustable so as to maintain the platform, or sluice supporting means, in a perfectly level or horizontal position with the result that the sluice, and other mechanism supported on the platform, will be disposed at the proper angle for the successful operation thereof.

Another object is to provide novel and improved means for adjusting the platform and skids thereof, and means for supporting the weight of the platform, to relieve the adjusting means, while the device is in operation.

A further object is to provide novel and improved means for holding the platform or bed, and the skids in position, against displacement, while in lowered or folded position.

Other objects and advantages will be apparent from the following description when taken in connection with the accompanying drawings:

In the drawings:

Figure 1 is a side elevation of an amalgamating machine showing the improved bed and skids.

Figure 2 is an end elevation of the same.

Figure 3 is a vertical transverse sectional view on the line 3—3 of Figure 1, looking in the direction of the arrows.

Referring particularly to the accompanying drawings, there is shown a staging including the longitudinal parallel side sills 10, between which extend the transverse beams 11, on which are supported the super-structure 12, carrying the amalgamating sluices and screen cylinder 13 and 14, respectively, and the engine platform 15.

Mounted in suitable brackets 16, on the

forward end of the staging, is a transverse shaft 17, and rockably engaged with the ends of the shaft are the bearing brackets 18, which are carried by the upper edges of the forward portions of the skids 19. These skids 19 extend longitudinally beneath the staging and are adapted to be swung vertically into different angles for resting on slopes of various degrees, so that the staging will lie in a horizontal plane. Extending from the rear end of each of the side sills 10 is a bearing bracket 20, through which is vertically disposed an elevating screw 21. Secured to the upper face of each of the brackets 20 is a housing 22 having openings 23 in its opposite sides through which project the opposite side portions of the nut 24, which is threadedly engaged on the screw 21. This nut is formed with a plurality of openings 25, for the reception of a suitable bar tool, for the purpose of rotating the nut to elevate and lower the stage. The lower end of each screw 21 is swiveled in a socket bearing plate 26, mounted on the upper edge of the rear end portion of the skid 19. Thus, by rotating the nut 24, the rear end of the staging can be raised and lowered, as the conditions and slope of the ground warrant. The skids 19 are connected, near their forward and rear ends, by means of the cross beams 27. On the outer side face of the rear end of each of the skids there is mounted a hook 28, which is arranged to be engaged by any one of a series of chain links 29, carried by the staging, and whereby, when the staging has been lowered onto the skids, the skids will be held against undue movement vertically, and the staging maintained against vertical movement.

When the staging has been elevated to the proper level, in accordance with the slope of the grade, on which the machine is being used, the weight would be sustained by the elevating screws 21. To obviate this, I place a block 30 on each of the skids 19, and a block 31 beneath each end of one or more of the cross beams 11, and then drive suitable wedges 32 between the adjacent ends of the blocks, to support the weight of the staging, and the mechanism carried thereby, and thus relieve the threads of the screws and nuts from injury. The upper ends of the chains 29 have the nut and screw means 41, for drawing the chains to move the skids and

staging toward each other, for the purpose of firmly binding the wedge blocks 32 and the blocks 30 and 31 together.

Centrally pivoted on the upper rear portion of the superstructure is a transverse rocker 33, and connected to the ends of this rocker, and extending downwardly and rearwardly from the machine, are the I-beams 34, beneath which is secured the metal bottom plate 35. Properly secured to the upper face of this plate 35, and extending in parallel relation to each other, and in parallel relation with and between the beams 34, are the rails 36, between which the elevating bucket 37 is arranged to slide. This bucket 37 has connected thereto a cable 38 which passes upwardly over a pulley 39, mounted on the superstructure, and by means of which the bucket is raised and lowered for the purpose of dumping the placer gravel into the hopper 40, at the upper end of the cylinder 14, from whence the gravel falls into the said cylinder.

The side beams 34 are pivotally connected to the ends of the rocker 33 for vertical swinging movement, while the rocker is pivotally supported for horizontal swinging movement, thus enabling the operator to move the bucket guideway into any vertical and horizontal position, within a given distance or radius.

What is claimed is:

1. A support for an amalgamator comprising a staging, skids movably connected with the staging, means for elevating and lowering one end of the staging with relation to the skids, means for supporting the weight of the staging independently of the elevating means, and means for drawing the staging and skids toward each other to bind the said supporting means.

2. A support for an amalgamator comprising a staging, skids movably connected at

one end to one end of the staging, elevating means between the other ends of the staging and skids respectively, means adjustable between the staging and the skids for supporting the staging independently of the elevating means, and means for drawing the staging and skids toward each other to bind the said adjustable means.

3. A support for an amalgamator comprising a staging, skids disposed beneath the staging and being pivotally connected at one end to one end of the staging, elevating and lowering screws operatively connected with the other ends of the staging and skids respectively, wedging means removably engaged between the staging and skids intermediate the screw and pivots of the skids for supporting the weight of the staging independently of the screws, and flexible tensioning means between the staging and skids for frictionally binding the wedging means.

4. A support for an amalgamator comprising a staging, skids pivotally connected to one end of the staging, elevating screws movably connected to the skids, guides on the staging receiving the screws slidably therethrough, housing on the guides, nuts in the housings receiving the screws threadedly therethrough, hooks on the sides of the skids, chains carried by the staging and engageable with the hooks, blocks engaging the staging and skids, wedges between the blocks for supporting the staging independently of the screws, and tensioning means between the chains and staging for drawing the chains to move the staging and skids toward each other for frictionally binding the wedges and blocks.

In testimony whereof, I affix my signature, in the presence of a witness.

HARVEY W. RICHARDS.
